UNITED STATES PATENT OFFICE.

MAXIME LORME, OF LONDON, ENGLAND.

ANTISKID-STUD.

1,065,949.

Specification of Letters Patent.

Patented July 1, 1913.

Application filed November 16, 1912. Serial No. 731,890.

To all whom it may concern:

Be it known that I, MAXIME LORME, a citizen of the Republic of France, residing at 9 Bread Street Hill, London, England, have invented a new and useful Improved 5 Antiskid-Stud, of which the following is a specification.

This invention relates to an improved stud for attachment to boots and shoes and more 10 particularly to the treads of yielding tires of the wheels of motor vehicles, with the object of lessening or eliminating the tendency of the tread to slide relatively to the surface of the road, the stud being of the kind in 15 which a plurality of asperities of unequal prominence are provided which will in succession come into contact with the road as the stud wears away.

According to the present invention the 20 central portion of the face of the head of the stud is concave and the surrounding portion thereof is conical and the asperities of unequal prominence consist of facets on the concave central portion.

25 The accompanying drawing shows alternative varieties of studs according to the present invention.

In this drawing:—Figures 1, 2 and 3 are 30 respectively a plan, a side elevation and a sectional elevation of one form of construction. Figs. 4, 5 and 6 are corresponding views of a modification.

35 In these figures, the face of the head of the stud which is presented to the road surface is concave in its central portion, the outside boundary being conical. The concave portion is so formed as to furnish sets of facets *a* situated at graduated distances

from the road surface. When the set which occupies the outer border of the hollow of 40 the stud surface becomes worn, another set of facets *a*, which is initially protected against wear by being situated within the hollow of the concave surface, comes automatically into operation. The outside 45 conical wall is formed with teeth *b* somewhat like those of bevel-wheels.

The construction shown in Figs. 4-6 differs from that last referred to in respect to 50 the fact that a set of asperities *c* are provided on the outer conical wall, the teeth *b* of the conical surface making contact with the road when the set *c* between the inner border of the cone and the outer border of the hollow becomes worn.

55 The shanks of the studs may be screw-threaded and screw-driver slotways may be formed in their heads to enable them to be screwed into the treads.

I claim:

1. In a non-slipping stud, a head having 60 a concave central face portion surrounded by a conical portion and facets on said concave portion.

2. In a non-slipping stud, a head having 65 a concave central face portion surrounded by a conical portion, facets on said concave portion and asperities at the edge of said concave portion.

In testimony whereof I have signed my 70 name to this specification in the presence of two subscribing witnesses.

MAXIME LORME.

Witnesses:
